UNITED STATES PATENT OFFICE.

THEODORE C. ROBERTS, OF NEW YORK, N. Y., ASSIGNOR, BY MESNE ASSIGNMENTS, TO
DICTAPHONE CORPORATION, OF NEW YORK, N. Y., A CORPORATION OF NEW YORK

CONNECTER PLUG.

Application filed August 18, 1931. Serial No. 493,478.

This invention relates to improvements in cable connections, and particularly in electrical plug-socket connections.

An object of the invention is to provide a structure adapted, when assembled in operative position, to relieve the cable-ends and their connections from any strain which may be put upon the cable itself.

Another object is to provide a device of this character which is simple and cheap to construct, easy to assemble and disassemble with its cable, and adapted to withstand rough handling.

In the use of plug-sockets on portable machines, such as dictation machines, the connection is often subject to considerable strain; and, in detaching the plug-socket, the cord is quite often jerked or pulled with such force as to loosen the terminal connections. So a further object of this invention is to provide a plug-socket which will take up all this strain in itself, and without transmitting any appreciable part of it to the terminal connections.

A further object is to provide such a structure which will provide complete and effective insulation between the terminals. To this end, means are provided for separating the interior of the connection into separate chambers for the respective terminal connections, so that the possibility of short circuiting is entirely eliminated.

With the above and other objects in view, as may hereinafter be suggested, one embodiment of the invention is shown in the accompanying drawings, and this will now be more fully described with reference thereto, and the invention finally pointed out in claim.

In the drawings—

Fig. 1 is a view, in side elevation, of the terminal-connection member of the device.

Fig. 2 is a rear end view, and—

Fig. 3 is a front end view of the same.

Fig. 4 is a view, in side elevation, of the cover member.

Fig. 5 is a rear end view, and—

Fig. 6 is a front end view of the same.

Fig. 7 is a sectional view of the completely assembled device, and showing the cord connected to the terminals, the means of relieving the cable strain therefrom, and the means of effectively insulating the terminals from each other.

Fig. 8 is a side elevation of one of the terminal posts.

Fig. 9 is a front elevation of the same.

Similar reference characters indicate corresponding parts throughout the several figures of the drawings.

Referring to the drawings, and particularly to Figure 7 thereof, the device, according to the present embodiment, comprises two main parts or members—one a terminal-connection member, and the other a cover member, both formed of suitable insulation material, preferably of a moldable phenol-condensation product or like substance.

The terminal-connection member (Fig. 1) comprises an intermediate exteriorly-threaded portion 10, a forwardly-extending reduced cylindrical portion 11, and a central flat barrier rib 12 extending rearwardly.

A pair of terminal posts (Fig. 7), of brass or other conductive material, are molded into the cylindrical portion 11, and extend in spaced relation from the front face of the portion 11 to and through the rear face of portion 10, and at each side of the barrier rib, as shown. The forward ends of the posts are disposed slightly below the surface of the portion 11, and are surrounded by countersunk areas 15 of portion 11, and are provided with sockets 16 adapted to be engaged by the usual plug terminals (not shown). The countersunk portions 15 are adapted to guide the plug terminals into the sockets of the posts, so that the plugs may be positively and quickly connected, and premature engagement with the posts prevented.

The posts are bent, as at 17, to offset the rear end portions, and are provided with pinched fins or flanges 18 and 19, (Figs. 8 and 9), adapted to firmly anchor the posts in the molded terminal-connection member. Flat plate portions 20 are provided upon the ends of the posts, and extend, when in assembled position, to each side of the barrier 12, and in parallel relation thereto. And upon these portions 20 are mounted terminal screws 21 for holding the looped ends of the conductor wires upon the plates, and in electrical contact thereto. The outer corners of the plates are bent outwardly, as at 22 and 23, in such manner as to aid in confining the wires upon the plates.

The cover member, (Figs. 4, 5, and 6), is

of substantially bottle-shape, and at its enlarged end is interiorly-threaded, as at 24, (Fig. 7), to engage the corresponding threads in the terminal-connection member.

5 At its small end 25, there is provided a restricted passage 26, and adjacent this, a larger-diameter portion 27 forming an annular curved shoulder 28 with the portion 26, and an annular curved shoulder 29 with the

10 main opening surrounding the terminal connections.

A metal sheath 30, (Figs. 4 and 7), is provided about the cover member, being secured by crimping, or spinning over the large end, 15 as at 31, (Fig. 4). This sheath is provided with surface knurling 32 to facilitate gripping of the device when assembling or disassembling.

In assembling, the cover member is first 20 slid over the cord 33, and the insulated end- portions 34 and 35 of the conductor wires are knotted, as at 36, the knot being of such size as not to pass through the restricted passage 26, but fitting into the portion 27 25 against the shoulder 28. The exposed wire ends 37 and 38 are looped, and are secured to the plate portions 20 by means of the screws 21; the cover member is then screwed into engagement with the terminal-connection member, as shown in Fig. 7, the cord 33 being free to revolve within the passage 26.

When thus assembled, the barrier 12 is located in close proximity to the recessed portion 27, as seen in Fig. 7, so as to limit 35 the movement of the knot inwardly of the terminal-connection member.

It is thus seen that there is provided in this structure a means of positively assembling the two members of the device, of effectively insulating the terminals from one another and from the exterior of the device, and so prevent short circuiting, and finally, of relieving the terminals of any tensional strain which may be put upon the cable. The metal sheath enclosing the device acts

as reinforcing, and eliminates all danger of breakage of the cover member when the wire knot is forced against it through heavy strains on the cable; it also adds appreciably to its appearance.

50 While the invention has been described as embodying certain features of construction and arrangement of parts, and adapted for a certain kind of use, it is understood that it is not so limited, but includes the broad conception of the various features disclosed, and contemplates changes within the spirit and scope thereof.

Having described one illustrative embodiment of the invention, what is claimed as 60 new, and for which Letters Patent is desired, is:

A device of the character described, comprising a terminal-connection member, terminal connection means carried by said member disposed in spaced relation, and having exposed means at their inner ends for securing the terminals of electric conductors, a barrier rib protruding from the member between the inner ends of the connection means, and a cover member detachably connected to the terminal-connection member, enclosing the terminal connections, and having an opening through which the conductors pass, a recessed portion within 70 the cover member disposed between the terminal connections and said opening, and being of greater diameter than said opening, the recess adapted to receive a knot or other enlargement formed upon the conductors to 75 withstand strains thereon, without transmission of such strains to the terminal connections, the barrier rib being located adjacent said recess and being adapted to limit the movement of the knot inwardly of the terminal-connection member.

80 Signed at Bridgeport in the county of Fairfield, and State of Connecticut, this 15th day of August, A. D. 1921.
